US00D905651S

(12) **United States Design Patent** (10) **Patent No.:** **US D905,651 S**
(45) **Date of Patent:** **** Dec. 22, 2020**

(54) **TELEVISION RECEIVER**

(71) Applicant: **SAMSUNG ELECTRONICS CO., LTD.**, Suwon-si (KR)

(72) Inventors: **Seungho Lee**, Guri-si (KR); **Eunah Kim**, Seoul (KR); **Jaewook Yoo**, Seoul (KR); **Jangho Kim**, Seoul (KR)

(73) Assignee: **SAMSUNG ELECTRONICS CO., LTD.**, Gyeonggi-Do (KR)

(**) Term: **15 Years**

(21) Appl. No.: **29/687,202**

(22) Filed: **Apr. 11, 2019**

(30) **Foreign Application Priority Data**

Oct. 12, 2018 (KR) 30-2018-0047061

(51) **LOC (12) Cl.** **14-03**

(52) **U.S. Cl.**

USPC **D14/126**; D14/239

(57) **CLAIM**

The ornamental design for a television receiver, as shown and described.

DESCRIPTION

FIG. 1 is a front perspective view of a television receiver, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The even-dash broken lines illustrating portions of the television receiver form no part of the claimed design.

1 Claim, 8 Drawing Sheets
